MAGNETIC MULTIVIBRATOR

Marvin Chodorow, New York, N. Y., assignor to
 Maguire Industries, Incorporated, a corpora-
 tion of New York

Application August 28, 1943, Serial No. 500,353

9 Claims. (Cl. 250—36)

My invention relates to a multi-vibrator, and more particularly such an apparatus wherein a pair of thermionic tubes, as a pair of magnetron tubes, are caused to conduct alternately, each tube influencing the conducting of the other. The invention is closely related to my copending patent application Serial No. 499,719, filed August 23, 1943, for Self-pulsing circuit.

One object of the invention is the provision of an electrical apparatus without moving parts, wherein alternate opposite pulses will be produced automatically. A further object is the provision of such an apparatus employing a pair of thermionic tubes, each being influenced or controlled by the other. Other objects and advantages of the invention will be apparent from the present specification.

Certain forms of the invention are shown by way of illustration in the accompanying drawing, in which—

Figure 1 is a diagrammatic sketch of an apparatus embodying the invention, and

Figure 2 is a diagrammatic sketch of an apparatus illustrating a variant form of the invention.

An important feature of the invention is the inclusion in a circuit of two thermionic tubes, together with means for periodically increasing the voltage across one or both tubes, and means governed by the action of each tube for increasing the required conducting voltage or opposition to conducting of the other tube. Obviously the invention is not limited to the use of two tubes.

In the embodiment of the invention illustrated in Figure 1, a circuit 10 is provided in which are connected two magnetron tubes 11 and 11^a. A source of E. M. F. (indicated by + and — signs) is conveniently included in the circuit 10 for energizing it.

For simplicity, the magnetron tubes 11 and 11^a are shown without the usual glass envelopes. The magnetron tube 11 comprises a filament cathode 13, connected across the terminals of a battery 14 and also connected at one end to the circuit 10. The cathode 13 is surrounded by a cylindrical anode 15, which is connected to the circuit 10. A condenser 12 is provided for building up the voltage across the magnetron tube 11; and as here shown the condenser is connected in the circuit in parallel with the tube 11. The magnetron tube 11^a comprises a similar cathode 13^a connected across the terminals of a battery 14^a and also connected at one end to the circuit 10. A similar cylindrical anode 15^a surrounds the cathode 13^a and is connected to the circuit 10. A

condenser 12^a is provided for building up the voltage across the magnetron tube 11^a, and in the present instance is connected in the circuit in parallel with the tube 11^a.

Thus if a positive voltage is applied by the circuit 10 across the tube: that is to say, between the filament cathode 13 or 13^a and the cylindrical anode 15 or 15^a, the tube will conduct.

As is well known, conducting of a cathode-anode tube of this kind may be influenced by a magnetic field appropriately applied to the tube. In the present embodiment a separate magnet 16, excited by a winding 17 unrelated to the circuit 10, is associated with the tube 11 for influencing

conducting of the tube, and a similar magnet 16^a, excited by a winding 17^a unrelated to the circuit 10 is associated with the tube 11^a for influencing conducting of that tube. In the present illustrative embodiment of the invention, each magnet is positioned with its field direction parallel to that of the corresponding cathode. Accordingly, each magnetic field will oppose conducting of the corresponding magnetron tube. The stronger the field of the separate magnet therefore, the higher will be the required conducting voltage, or the voltage at which the corresponding magnetron tube will conduct.

In order that conducting of the tube 11 may influence conducting of the tube 11^a, an electro-magnet 18^a is disposed adjacent the tube 11^a with its winding 19^a connected in series with the tube 11. In the present embodiment of the invention the electro-magnet 18^a is coaxial with the magnetron tube 11^a and the separate magnet 16^a, and its winding 19^a is so directed that the field of the electro-magnet 18^a augments that of the separate magnet 16^a. It will therefore be apparent that when the electro-magnet 18^a is energized the resulting magnetic field, augmenting the field of the separate magnet 16^a, will provide increased opposition to conducting of the tube 11^a, in consequence of which a higher voltage will be required to cause the tube 11^a to conduct. Since the winding 19^a of the electro-magnet 18^a is connected in series with the magnetron tube 11, conducting of the tube 11 will increase the opposition to firing of the tube 11^a; and if the tube 11^a is conducting, discharge of the tube 11 may extinguish it.

In similar manner, conducting of the tube 11^a may influence conducting of the tube 11. To this end an electro-magnet 18 is disposed adjacent the tube 11 with its winding 19 connected in series with the tube 11^a. As here shown, the electro-magnet 18 is coaxial with the magnetron

tube 11 and the separate magnet 16 and its winding 19 is so directed that the field of the electro-magnet 18 augments that of the separate magnet 16. Thus, it will be evident that when the electro-magnet 18 is energized the resulting magnetic field augmenting the field of the separate magnet 16, will provide increased opposition to conducting of the tube 11, in consequence of which a higher voltage will be required to cause the tube 11 to conduct. The winding 19 of the electro-magnet 18 being connected in series with the magnetron tube 11^a, conducting of the tube 11^a will increase the opposition to conducting of the tube 11; and if the tube 11 is conducting, discharge of the tube 11^a may extinguish it.

Alternate conducting of the magnetron tubes 11 and 11^a, each influenced by the other, will occur as follows: Assume that the tube 11 is conducting. The electro-magnet 18^a is thereby energized, and the combined fields of the separate magnet 16^a and the electromagnet 18^a will act to oppose conducting of the tube 11^a. When the condenser 12^a has built up sufficient voltage across the tube 11^a to overcome this opposition to conducting, the tube 11^a will conduct. Thereupon the winding 19 of the electro-magnet 18 is energized, and the field of the latter magnet augments that of the separate magnet 16 in opposing conducting of the tube 11, and this tube is quenched. When the tube 11 is quenched, no energy is supplied to the winding 19^a of the electro-magnet 18^a, and its field drops to zero. This reduces the field across the tube 11^a, and hence its opposition to conducting. The tube 11^a therefore continues to conduct as the condenser 12^a discharges and the voltage across the tube 11^a drops.

When the condenser 12 has built up sufficient voltage across the tube 11 to overcome opposition to conducting imposed upon it by the magnets 16 and 18, the tube 11 conducts. The magnet 18^a is thereby energized and the tube 11^a is quenched. Thereupon the magnet 18 is de-energized, its field drops to zero, the opposition to conducting of the tube 11 is reduced, and the tube 11 continues to conduct.

The cycle is thus repeated.

From the foregoing it will be apparent that, if energy is supplied to the circuit 10, as by means of the source of E. M. F., and if one tube, as the tube 11, is first caused to conduct, the tubes 11 and 11^a will then conduct alternately and automatically as long as energy is supplied to the circuit.

Variable resistances 20 and 20^a are interposed between the condenser 12 and 12^a respectively and the corresponding magnetron tubes 11 and 11^a. Another variable resistance 21 is included in the shunt in which the condenser 12 is connected; and a corresponding variable resistance 21^a is included in the shunt in which the condenser 12^a is connected. Finally, variable resistances 22 and 22^a are interposed between the source of E. M. F. and the respective shunts containing the condensers 12 and 12^a. By suitably adjusting these variable resistances and by suitable selection of the capacities of the condensers 12 and 12^a, the frequency and duration of the pulses may be controlled.

A variable condenser 23 and a resistance 24 are connected in parallel in the circuit between the cathode 15 of the magnetron tube 11 and the shunt containing the condenser 12. A corresponding variable condenser 23^a and a resistance 24^a are connected in parallel between the

cathode 15^a of the magnetron tube 11^a and the shunt containing the condenser 12^a. Thus the condenser-resistance unit 23, 24 is connected in series with the tube 11, and the condenser-resistance unit 23^a, 24^a is connected in series with the tube 11^a. Each variable condenser is so adjusted that it provides approximate series resonance in the circuit, so that the voltage drop across the winding of the electro-magnet with which it is in series (which leads the current) will not extinguish the corresponding tube before the field of the magnet is established.

Obvious variations in the circuit and the combinations of electrical units will, of course, suggest themselves to those skilled in the art.

For example, it is possible to control conducting of both tubes and timing of the pulses by proper unbalance of the circuit constants. In the embodiment on the invention disclosed in Figure 1, such unbalance will be between the circuit constants on one side of the source of E. M. F. and those on the other. In this case conducting and quenching of one tube alone will control the timing and duration of the pulses. Such unbalance may cause the tube 11, for instance, to conduct and be extinguished as a result of its own circuit constants alone. Because of this condition, conducting and quenching of the tube 11^a will follow action of the tube 11, and the only function of the circuit constants related to the tube 11^a is to maintain this tube in conducting or extinguished condition until that condition has been changed by further action of the tube 11.

The two halves of the circuit may be made as unsymmetrical as desired to give a wide choice of pulses.

Still another possible variation is the addition of an alternating current excitation to each of the separate magnets 16 and 16^a. Such additional excitation may be applied by separate windings (not shown) or may be superimposed on the direct current windings 17 and 17^a respectively. Since the additional A. C. excitation causes the field to fluctuate with the timing of the A. C., conducting of the apparatus may be synchronized with the A. C.—directly or in multiples or fractions of its timing.

The embodiment of the invention shown in Figure 2 illustrates a further variation. In this embodiment no resistance-capacity shunt is employed with the magnetron tube 11^a, but the circuit is connected directly across this tube. In this form of the invention the tube 11^a is caused to conduct and is extinguished by action of the tube 11 only. The time intervals in this form of the invention depend solely upon the circuit constants of the tube 11.

The forms of the invention here particularly described and illustrated are presented merely to indicate how the invention may be applied. Other forms, differing in detail but not in principle from those here set forth, and coming within the proper scope of the appended claims, will readily suggest themselves to those skilled in the art.

I claim:

1. A multi-vibrator comprising a circuit, two magnetron tubes in said circuit, means for periodically increasing the voltage across one of said tubes, and electromagnetic means governed by the action of one tube for increasing the opposition to conducting of the other tube.

2. A multi-vibrator comprising a circuit, two magnetron tubes in said circuit, means for periodically increasing the voltage across one of said tubes, and electromagnetic means governed by the

action of one tube for increasing and decreasing the opposition to conducting of the other tube.

3. A multi-vibrator comprising a circuit, two magnetron tubes in said circuit, means for periodically increasing the voltage across each tube, and an electro-magnet excited by the action of each tube for increasing the opposition to conducting of the other tube.

4. A multi-vibrator comprising a circuit, two magnetron tubes in said circuit, means for increasing the voltage across each tube, and an electro-magnet excited by the action of each tube for increasing and decreasing the opposition to conducting of the other tube.

5. A multi-vibrator comprising a circuit, two magnetron tubes in said circuit, means for periodically increasing the voltage across one of said tubes, and an electro-magnet connected in series with each tube and disposed adjacent the other tube for increasing the opposition to conducting of the other tube.

6. A multi-vibrator comprising a circuit, two thermionic tubes in said circuit, an electro-magnet connected in series with one of said tubes disposed adjacent the other of said tubes to influence its conducting, a second electro-magnet connected in series with the other of said tubes disposed adjacent said first-named tube to influence its conducting, and a condenser in circuit with one of said tubes for discharging through said tube to cause it to conduct.

7. A multi-vibrator comprising a circuit, two magnetron tubes in said circuit, an electro-magnet connected in series with one of said tubes disposed adjacent the other of said tubes to influence its conducting, a second electro-magnet connected in series with the other of said tubes disposed adjacent said first-named tube to influence its conducting, and a separate condenser in circuit with each of said tubes for discharging through said tube to cause it to conduct.

8. A multi-vibrator comprising a circuit, two magnetron tubes in said circuit, an electro-magnet connected in series with one of said tubes disposed adjacent the other of said tubes to influence its conducting, a second electro-magnet connected in series with the other of said tubes disposed adjacent said first-named tube to influence its conducting, and a condenser connected in parallel with one of said tubes for discharging through said tube to cause it to conduct.

9. A multi-vibrator comprising a circuit, two magnetron tubes in said circuit, an electro-magnet connected in series with one of said tubes disposed adjacent the other of said tubes to influence its conducting, a second electro-magnet connected in series with the other of said tubes disposed adjacent said first-named tube to influence its conducting, and a separate condenser connected in parallel with each tube for discharging through said tube to cause it to conduct.

MARVIN CHODOROW.
